EDWIN C. SWANSON, OF ROCKFORD, ILLINOIS, ASSIGNOR TO GREENLEE BROS. & CO., OF ROCKFORD, ILLINOIS, A CORPORATION OF ILLINOIS

HOLE CUTTER

Application filed March 1, 1929. Serial No. 343,592.

This invention relates to cutters for making circular holes in sheet metal particularly adapted for use in making or enlarging holes in fuse boxes, junction boxes, switch boxes and the like.

In the installation of conduit for electrical equipment and wiring it is customary to insert metal boxes at appropriate points in the system such as fuse boxes, switch boxes, starting boxes and the like. These boxes are usually purchased ready-made and in many cases are provided with a number of "knock-outs" or potential openings for attaching the conduit, formed by only partially cutting through the metal leaving the blank therein, the appropriate one to be removed by a sharp blow from a hammer or other tool at the time of installation. While these "knock-outs" serve the purpose admirably when conduit of the normal size is used, they must, of course, be enlarged or new openings cut to accommodate larger conduit. This has, in the past, been accomplished in most cases by drilling small holes on the periphery of the circle desired to be cut and sawing the metal therebetween with a hacksaw. Other equipment for this purpose has been provided, however, such as tools which cut by removing the metal, circular band saws, and stamping dies.

Those agencies which act by removing the metal, while perhaps the most popular, are far from satisfactory, for when the metal has been removed until but a thin layer remains the tool has a tendency to dive through the layer taking too large a "bite" and either breaking or "freezing" the tool. Circular band saws have a tendency to "freeze" and turn hard because of the small clearance between the sides of the cut and the distortion of the saw. Stamping dies require too much power to be of portable use except on the very lightest metal.

My invention contemplates the provision of a series of circular discs of varying sizes any one of which may be held against the metal by means of a bolt passing through the center. A rotatable bar is mounted on the bolt on the opposite side of the metal and is equipped with sharp edged wheels

which, when the bar is turned, inscribe a circle corresponding to the periphery of the disc beneath. Pressure is applied between the disc and the wheels to progressively sheer the metal.

One of the objects of my invention is the provision of means for cutting circular holes in sheet metal progressively and with comparative ease.

I have also aimed to provide a cutter relatively light in weight and small in size to permit its use in cramped or limited quarters, and adapted to cut holes of a number of different sizes.

Still other objects of the invention will be apparent to those skilled in this art from the following description and accompanying drawings in which:

Figure 1 is a side elevation of the hole cutter in a position for operation showing a sheet of metal between a disc body and the cutter wheels;

Fig. 2 is a top view of the cutter equipped with the disc body shown in Fig. 1;

Fig. 3 is a section on the line 3-3 of Fig. 2 showing cutter in use with a disc body similar to that shown in Fig. 1, but of different size; and

Fig. 4 is a section on the line 4-4 of Fig. 3 showing the supporting wedge in position.

The machine consists essentially in a supporting bolt upon which is mounted a disc, a cutter arm carrying cutter wheels projecting downward at the periphery of the disc, the metal being cut between the two by rotating the cutter arm and simultaneously applying pressure through suitable means such as a nut at the end of the bolt. The discs are adapted to be changed for others of different diameters and the cutter wheels are capable of being changed to correspond therewith.

A bolt 6, best shown in Fig. 3 has a wide flat head 7 adapted to support a disc body designated generally by 8. A key 9 in the bolt cooperates with a slot 10 in the disc and prevents the bolt from turning therein. The disc 8 is circular in shape and provided with parallel sides 11 and 12 of different radii, the side 11 being adapted to rest against the metal when the smaller hole is being cut and

the side 12 when the larger hole is desired. The edges of the disc portions 13 and 14 are ground smooth to present a sharp angle and a smooth face to the action of the cutter 5 wheels presently to be described and each disc portion is undercut or relieved annularly at a distance from its angular cutting edge to allow for grinding. A plurality of these disc bodies having faces of varying radius 10 may be employed to permit the machine to be used to cut holes of varying sizes. I have shown two disk bodies adapted for use in cutting holes of four different sizes, the larger disc being shown in Figs. 1 and 2 (having reference numerals 11', 12', 13' and 14') and the smaller in Fig. 3.

The supporting bolt with the disc attached 15 is designed to be inserted through a small hole in the stock or metal to be cut which 20 may be made therein with a drill of the ordinary type. Where metal boxes provided with "knock-outs" are being used one of these may be removed to act as an opening for the bolt. A cutter arm 15 is rotatably mounted on the 25 supporting bolt at its center. A nut shaped portion 16 is fixedly attached to the cutter arm by means of a flange 17 and pin 18, and extends upward around the supporting bolt 6 providing a means for turning the cutter bar about said bolt with a wrench. The bar has recessed portions 19 near each end thereof which form the lower part of the bar into a central hub or bearing portion 20 and end flanges 21 and serve to receive the cutting 30 mechanism. Bearing pin 22 passing through the recesses fit closely at one end into holes 23 in the hub portion and are threaded at the other end into the flanged ends at 24. The heads of the pins are provided with slots 35 whereby the pins are easily removed with a screw driver. Bushings 25 surround the pins through the entire length of the recesses and have flanges 26 at one end to act as spacing members. Mounted upon the bushings are 40 the spacing blocks 27 and the cutter wheels 28. The spacing blocks, in this case of triangular form shown in outline in Fig. 4, are two in number on each bushing and serve to permit the cutter wheel to be moved to different positions along the bushing. They 45 also serve, because of their flat upper edges 29, which rest firmly against the cutter arm, to support the pins and bushings against the upward thrust on the cutter wheels when the 50 latter are being forced into the metal. The cutter wheels are identical and each consists of a hub portion 30 and a beveled cutting edge 31. The cutting mechanism may be 55 easily and quickly removed for rearrangement by removing the bearing pin 22. Spacing blocks of different sizes or any equivalent means may be employed for locating and holding the cutter wheels in set position.

The disc 8 and the cutter wheels are drawn 60 together against the metal by means of a nut 65

32 threaded on the upper end of the bolt 6. The threads are cut to advance the nut slowly and thus give a close regulation of the cutting speed and power required for turning the cutter arm. Interposed between the nut 70 like portion 16 of the cutter arm and the nut 32 is a lock washer 33 having a projection 34 extending into a slot 35 of the bolt 16 to prevent the turning movement of the cutter bar from being transmitted to the nut 32 and disturbing its setting.

The operation of my improved cutter will be seen to be at once effective and simple. The operator first provides a small opening 80 large enough for the bolt 6 in the metal by means of a drill or otherwise. The supporting bolt with the proper sized disc 8 thereon is inserted in the opening. The cutter wheels are set on the pin 22 in a position to cooperate in a self evident manner with the disc chosen. 85 This may be done by interchanging the cutter wheels with either of the spacing blocks or by reversing the bushings 25 to place the flanges at the opposite side of the recesses. The cutter bar with the cutter wheels properly placed is slipped over the bolt 6 on the opposite side of the metal from the disc. The lock washer 33 is placed upon the bolt and the nut 32 screwed thereon. The nut is drawn tight and the cutter bar turned by means of 90 a wrench applied to the nut-like portion 16. The nut 32 is intermittently drawn up as the cutter wheels make their way through the metal and release the pressure.

My cutter will be seen to offer a number of 100 distinct advantages. The speed at which the metal is cut and consequently the force required to turn the arm may be regulated at will. A number of different sizes of holes may be cut with the same cutter. The stock 105 is not bent but progressively sheared through between the cutter wheels and the peripheral edge of the disc. The amount of space required to operate the device is small and holes may be cut near corners and where the operating space is narrow. The device is sturdy, 110 not easily broken, and long lived.

While I have shown and described a particular embodiment of my invention for purposes of illustration I am aware that numerous changes and modifications may be made without departing from the spirit and scope 115 of the invention as described and claimed.

I claim:

1. A circle cutter comprising a circular disc, supporting means at the center thereof adapted to pass through a hole in the stock and support the disc closely thereto, a cutter arm rotatably mounted upon said supporting 120 means on the opposite side of the stock from said disc, cutter wheels rotatably mounted on the cutter arm and projecting from the bottom side thereof in a position to inscribe a circle of the same diameter as the disc below, 125

and means for applying pressure between the cutter arm and the circular disc.

2. A circle cutter of the character described having a disc body each end of which is of a diameter different from the other and adapted to be seated in operative position against one side of a metal sheet to be cut, and cutting wheels adapted to bear against the opposite side of the metal sheet opposite the periphery of either end of said disc body to cooperate therewith in shearing the metal.

3. A circular cutter comprising a circular disc each end of which presents a flat circular face of a diameter different from the other adapted to rest in an operative position against one side of a metal sheet to be cut, a plurality of cutting wheels adapted to bear against the opposite side of the metal sheet opposite the periphery of the disc in operative position to cooperate therewith in shearing the metal, means for rotatably supporting said cutting wheels and permitting adjustment thereof to cooperate with either disc diameter, and independently operable means for applying pressure between said wheels and said disc to cut the interposed metal sheet.

4. A circle cutter of the character described having cutters, a rotatable cutter carrying part adapted to be positioned at one side of a metal sheet to be cut, a center bolt adapted to pass through the metal sheet and to provide bearing support for said cutter-carrying part on which the latter turns, and a disc body mounted on said center bolt at the side of the metal sheet opposite from said cutter-carrying part, said disc body having flat circular ends each of different diameter from the other and adapted to seat in an operative position against the metal sheet and determining the diameter of the hole to be cut, the cutters being adjustable to the diameter of the hole to be cut as determined by the disc end in operative position, and means for manually applying pressure, independent of said cutter carrying part, between the cutter-carrying part and the disc to cut the interposed metal sheet.

5. A circle cutter having a central bolt adapted to be located in a hole in a metal sheet, a disc secured on said bolt at one side of the metal sheet, a cutter arm rotatable upon said bolt at the opposite side of the metal sheet equipped with cutting wheels for cutting the interposed sheet, means for applying pressure between said disk and said cutter arm to effect the cutting, each cutting wheel being mounted to rotate on an elongated bearing on the cutter arm radial with respect to the center bolt, and interchangeable bearing blocks on the said bearings adapted to hold the cutting wheels in location thereon and to permit setting of said cutting wheels in different positions to vary the diameter of the cut.

6. A circular cutter as set forth in claim 5, in which the bearing blocks have thrust contact against the cutter arm to take the thrust from the cutter.

7. A circular cutter as set forth in claim 5, in which each cutting wheel and one or more spacing blocks are mounted on a bushing and each bushing in turn is mounted on a bearing pin carried by the cutter arm.

8. A circle cutter having a cutter arm rotatable about a center locating means, diametrically disposed bearing pins on the cutter arm, a bushing on each bearing pin, a cutting wheel on each bushing, and spacing blocks mounted on the bushings, said bushings, cutting wheels and spacing blocks being adjustable to effect different diameters of cuts.

9. A circle cutter comprising a center bolt adapted to be located in an opening in a metal sheet to be cut, means adapted to be non-rotatably mounted on the bolt at one side of the metal sheet having a plurality of cutting edges, any one of which may be placed in operative position thereagainst, a cutter arm adapted to be positioned on the bolt at the opposite side of the metal sheet equipped with cutting means complementary to said cutting edges and adapted to be rotated about the center bolt, and means operative between the center bolt and the cutter arm to apply pressure between the cutting means and said first mentioned means to effect cutting of the metal when the cutter arm is rotated.

10. A circle cutter comprising means having a plurality of cutting edges of different diameters for selective transposition next to the sheet to be cut, a supporting bolt passing through the center thereof and attached thereto adapted to pass through a hole in the stock to be cut, a cutter arm rotatably mounted upon said supporting bolt on the opposite side of the stock from said means having recessed portions therein, bearing pins passing through said recessed portions and seated at either end in said arm, a cutter wheel and a plurality of spacing blocks mounted upon each of said bearing pins adapted to be interchanged in position to move the cutter wheel in and out upon the pin to cooperate with said cutting edges, and a nut threaded on said supporting bolt to be turned downward in bringing the cutter wheels and said means together and to bring a desired pressure upon the metal therebetween.

11. A circle cutter comprising means having a plurality of cutting edges of different diameters for selective transposition next to the sheet to be cut, a supporting bolt passing through the center thereof and attached thereto adapted to pass through a hole in the stock to be cut, a cutter arm rotatably mounted upon said supporting bolt on the opposite side of the stock from said means and having

recessed portions therein, bearing pins passing through said recessed portions and seated at either end in said arm, bushings on said pins, cutter wheels rotatably mounted upon said bushings and projecting from the bottom side of said cutter arm in a position to inscribe a circle of the same diameter as the cutting edge next to the metal, spacing blocks mounted on said bushings adapted to support the bushings and hold the cutter wheel in its rotatable position while permitting the same to be moved in conjunction with the cutting edges to cut different sizes of holes, and a nut threaded on said supporting bolt adapted to be turned downward to bring said means and cutter wheels closer together and place a desired pressure therebetween.

12. In a circle cutter a cutter arm comprising a bar having a central pivotal opening, recessed portions near each end and a central projecting portion for cooperation with a wrench or other tool in turning the arm, bearing pins passing horizontally through each of said recessed portions and seated at either end in said arm, bushings having an annular projecting portion at one end mounted upon said bearing pins, a cutter wheel, and a plurality of spacing blocks mounted upon said bearing pin and bushing in each recess, said blocks being adapted to cooperate with the cutter arm surface to support the bushing and bearing pin and to be interchangeable with said cutter wheel permitting the latter to be used in a series of different positions in cutting holes of different sizes.

13. A circle cutter comprising a center bolt adapted to be located in an opening in a metal sheet to be cut, a cutter disc adapted to be non-rotatably mounted on the bolt at one side of the metal sheet, a cutter arm adapted to be positioned on the bolt at the opposite side of the metal sheet equipped with cutting means complementary to the cutter disc and adapted to be rotated about the center bolt, means operable between the center bolt and the cutter arm to apply pressure between the cutting means and the cutter disc to effect cutting of the metal when the cutter arm is rotated, and means for preventing rotation of the cutter arm from being transmitted to the last mentioned means.

In witness of the foregoing I affix my signature.

EDWIN C. SWANSON.
